(57) **CLAIM**

I claim the ornamental design for a bottle holder, as shown and described.

DESCRIPTION

FIG. 1 is a front view of a bottle holder, showing my new design;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is a top perspective view thereof; and,

FIG. 8 is another top perspective view thereof, showing the bottle holder in a position of use with an exemplary bottle. The broken lines are shown for the purpose of illustrating environmental subject matter of an exemplary bottle and form no part of the claimed design.
